US0D1058406S

(12) **United States Design Patent** (10) **Patent No.:** **US D1,058,406 S**
(45) **Date of Patent:** **** Jan. 21, 2025**

(54) **ANTI-THEFT VIDEO DOORBELL MOUNT
BRACKET**

(71) Applicant: **Shenzhen Guangteng Trading Co.,
Ltd**, Shenzhen (CN)

(72) Inventor: **Yujun Pan**, Shenzhen (CN)

(73) Assignee: **Shenzhen Guangteng Trading Co.,
Ltd**, Shenzhen (CN)

(**) Term: **15 Years**

(21) Appl. No.: **29/960,721**

(22) Filed: **Sep. 2, 2024**

(51) **LOC (15) Cl. 10-05**

(52) **U.S. Cl.**

(57) **CLAIM**

The ornamental design for an anti-theft video doorbell mount bracket, as shown and described.

DESCRIPTION

FIG. 1 is a front perspective view of an anti-theft video doorbell mount bracket, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The broken lines in the drawings illustrate the portions of the anti-theft video doorbell mount bracket, which form no part of the claimed design.

1 Claim, 8 Drawing Sheets
